M. B. FRANCKLYN

DECORATIVE ART

Filed March 30, 1921

INVENTOR
MARY BRENDA FRANCKLYN
BY *Chas. E. Townsend*
ATTY

UNITED STATES PATENT OFFICE.

MARY BRENDA FRANCKLYN, OF REDWOOD CITY, CALIFORNIA.

DECORATIVE ART.

Application filed March 30, 1921. Serial No. 456,948.

To all whom it may concern:

Be it known that I, MARY BRENDA FRANCKLYN, a British subject, residing at Redwood City, in the county of San Mateo 5 and State of California, have invented new and useful Improvements in Decorative Art, of which the following is a specification.

This invention relates to a decorative art, 10 and especially to improvements in the manufacture of ornamental window screens and the like.

One of the objects of the present invention is the production of an article of the 15 class specified which will be of a permanent lasting nature; flexible to a certain degree; substantially heat-proof; semi-transparent; weather and damp-proof; and above all sufficiently open to permit a free circulation of 20 air.

Another object of the invention is the provision of a filler for masking or closing the interstices of predetermined areas of a wire screen; to coat and surface the same; 25 and to permit varying designs to be readily formed and painted thereon; further to provide a filler or masking agent of a semi-transparent nature which when painted or otherwise decorated will produce the effect 30 of a stained glass in certain instances, textile ornamented fabrics in other instances, and in fact any design or decoration desired.

Further objects and features of the invention 35 will be later referred to, upon referring to the accompanying drawing wherein the figure is a front view of a window screen showing it ornamented by my method.

Referring to the drawing in detail, A indicates a coarsely woven fabric, such as wire 40 screen or the like, B a frame supporting the same, and C the masked and decorated portion of the screen.

In the process of preparing the fabric, I 45 first subject the same to a suitable cleansing bath in order that all foreign particles and grease will be properly removed therefrom. After this operation the fabric is coated with paint, enamel or a similar material to 50 protect the same against rust. This may be accomplished either by dipping the fabric directly in a solution, by spraying the same or by applying it with a paint-brush. Care should, however, be taken that the interstices 55 of the screen are not closed as one of the features of the present invention is the

provision of a screen of this character in which air is permitted to freely circulate even though portions thereof are closed and decorated. After the coating material has 60 been applied, it is obvious that the screen should be dried for a suitable period before it is further proceeded with.

The next step in the method of manufacturing and preparing screens by my method 65 consists in applying a masking agent to that area of the screen which it is desired to decorate. To accomplish this I take one quart of water and two and one-half ounces of gelatine glue. This glue is dissolved in 70 water by heating, and when completely dissolved is cleared by adding the white of one egg to the quart of dissolved glue and water. The egg shell is also crushed and added and the mixture is gradually brought 75 to the boiling point, care being taken that the mixture is stirred all the time to prevent burning. When thoroughly boiled, the temperature is reduced so that it will simmer 80 gently for about one-half hour, no stirring taking place at this time as the object of adding the white of an egg and the egg shell is to clear the glue. After simmering for one-half hour the entire mixture is permitted to cool and when thoroughly cool is 85 strained through a cloth or any other suitable filtering medium. One and one-half ounces of plaster of Paris is then added to the glue solution and once more brought to the boiling point; the entire mixture being 90 constantly stirred during the addition of the plaster of Paris, and thereafter, and a small amount of carbolic acid may be also added if desired to prevent decomposition 95 of the glue if it should be permitted to stand for a period of a few days or weeks. When the mixture of water, glue and plaster of Paris has been prepared, and while it is kept at a boiling temperature, it is in readiness 100 to be applied to the screen.

By referring to the drawing, we will suppose that the screen is to be decorated as shown. The masking agent or the glue preparation just described is then applied so that the area covered by the decoration will 105 be the only area which will be masked. The preparation is applied with a flat paint-brush and the preparation has such a consistency that it will close the interstices of the area to which it is applied and as such will form a 110 flat smooth surface which becomes fairly hard when thoroughly dried. The glue so-

lution is semi-transparent and it is, practically speaking, heat-proof. After the glue solution, or what may be termed the masking agent, has been applied and has been permitted to thoroughly dry, it is obvious that the screen is ready for the reception of the colors. In this instance I preferably employ oil paints; said paints being preferably semi-transparent to permit the light to pass therethrough. After the paint has dried, I finally complete the entire operation by coating both sides of the screen with one or more coats of shellac. This is important as it not only gives brilliancy to the decoration, but it further gives added protection against moisture, heat, cold, etc. It should be understood that when the last coating of shellac is applied, that care should also then be taken that the interstices of the screen are not closed as free circulation of air is desired through the major portion of the screen.

One of the most important features of the present invention is the fact that the masking agent, to-wit, glue and plaster of Paris, is covered with oil paint. This is a very important feature as it renders the masking agent completely moisture, water and damp-proof. The shellac coating, while preferably employed, may be eliminated under certain conditions.

The present method of decoration is not only limited to window screens constructed of wire or cloth, but can obviously be applied to any coarse fabric where decorations of one form or another are desired, for instance it might be advantageously employed in connection with fire screens, stage scenery or otherwise.

In actual practice I find that by employing a semi-transparent filler or masking agent, and by covering the masking agent with semi-transparent colors, practically any decorative effect can be obtained, for in-

stance a stained glass window may be easily imitated, a lace curtain effect, and ornamented textile fabric imitations can be easily obtained; the brilliant and final effect produced being largely depended upon the transparency of the masking agent and the oil colors employed.

Having thus described my invention, what I claim and desire to secure by Letters Patent is—

1. The herein described process of manufacturing decorative window screens having transparent and semi-transparent areas which consist in coating a coarse wire screen to protect the screen against rust without filling the interstices thereof and applying a semi-transparent masking agent consisting of a filler of glue and plaster Paris to predetermined areas of the screen to fill the interstices of said areas, painting the masked areas with semi-transparent oil colors to decorate the same and to render the masking agent water and damp proof, while preserving the semi-transparent character of the painted areas and then shellacking both sides of the screen without filling the interstices of the open portion of the screen.

2. A new article of manufacture, a decorative screen having transparent and semi-transparent areas comprising a coarse wire screen having a coating to protect the screen against rust without filling the interstices thereof, a semi-transparent masking agent consisting of a filler of glue and plaster Paris filling the interstices of certain areas of the screen and forming semi-transparent areas and having decorative coatings consisting of semi-transparent oil colors which renders the masking agent water and damp proof, and a shellac coating on both sides of the screen, the interstices of the undecorated areas being open.

MARY BRENDA FRANCKLYN.
